FLUORESCENT LIGHT FIXTURE

Eric B. Hallman, Philadelphia, Pa., assignor to
Electric Service Manufacturing Company, Phil-
adelphie, Pa., a corporation of Pennsylvania

Application July 20, 1945, Serial No. 606,184

2 Claims. (Cl. 173—328)

1

This invention relates to lamp sockets and more particularly to an improved construction of socket for double-ended tubular discharge lamps, such as fluorescent lamps.

Heretofore and prior to the present invention, tubular discharge lamps of the type having a pair of spaced contact or terminal prongs at their opposite ends have depended for their securement in the sockets respectively provided for the pronged ends thereof upon the frictional engagement of the terminal prongs with the spring metal contact elements conventionally employed in the sockets. This has proved not to be entirely satisfactory, particularly in the case where the lamp is subject to vibration, as where it is installed as a lighting fixture in railway vehicles, buses and other such conveyances.

Accordingly, it is among the principal objects of the present invention to provide as an auxiliary to the lamp socket means independent of the lamp prongs for supporting the lamp in position, thereby relieving the prongs of the weight of the lamp and at the same time insuring the lamp against its accidental displacement from its sockets even when subject to the most severe vibration.

A further object is to provide means in association with the conventional sockets for a tubular discharge lamp which are operative to releasably lock the lamp in supported position between its end sockets, said means being simple and inexpensive in design and construction as well as readily operable to release the lamp from its sockets for purposes of replacement, maintenance and repair.

Other objects and advantages of the invention will appear more fully hereinafter, it being understood that the present invention consists in the combination, construction, location and relative arrangement of parts, all as described in detail hereinafter, as shown in the accompanying drawings and as finally pointed out in the appended claims. In the said accompanying drawings, Figure 1 is an exploded view in perspective showing the lamp-supporting means of the present invention as employed in a fluorescent lighting unit of the type such as might be used more particularly in the interior of passenger vehicles;

Figure 2 is an elevational view of the lamp socket showing in association therewith the lamp supporting means in unoperative position;

Figure 3 is a view similar to Figure 2 but showing the lamp supporting means rotated into operative position;

2

Figure 4 is a sectional view taken substantially along the line 4—4 of Figure 2;

Figure 5 is a sectional view taken substantially along the line 5—5 of Figure 3;

Figure 6 is a perspective view of the auxiliary lamp supporting means per se; and

Figure 7 is a perspective view of the said means shown operatively associated with the lamp socket.

10 Referring now to the drawings and more particularly to Figure 1 thereof, it will be observed that the present invention has been shown as applied to a fluorescent lighting unit of the type suitable for installation in a passenger vehicle, 15 although it is to be understood, of course, that the present invention is adapted for use generally in all types of fluorescent lighting units having end sockets for reception of the pronged ends of the lamp. In the unit illustrated in Figure 1, these end sockets are designated by the reference numeral 10 and are respectively mounted upon the end support members 11—11 of the unit between which extends a suitable reflector or shield 12. The tubular discharge lamp 13 is of the well-known conventional type having at each of its opposite ends a pair of contact prongs 14—14, each pair of which is received within a corresponding pair of spring contact elements 15—15 suitably secured respectively within the open-ended slots 16—16 of each socket 10.

In accordance with the principles of the present invention, these sockets 10 are each of circular outline and are respectively secured to the end supporting brackets 11—11 of the lighting unit 35 by a pair of screws 17—17 or the like, the rear face of each socket being maintained free of its supporting bracket by spacing washers 18—18 of insulating material which serve also to insulate the socket from its supporting bracket. In its properly mounted position, the open ends of the slots 16—16 of the socket extend downwardly so as to facilitate insertion and removal of the pronged ends of the lamp into the socket from the bottom of the lighting unit, the terminal prongs 14—14 of the lamp being frictionally engaged by the spring contact elements 15—15.

To prevent unintentional or accidental displacement of the lamp from its sockets, each of the latter is provided with a lamp-retaining collar 19 of the form most clearly shown in Figures 6 and 7. This collar is in each case provided with a circumferentially continuous body portion 20 having at rear edge an inwardly turned flange 21 which fits against the rear face of the circular body portion of the socket 10 at the same time,

that the annular body portion 20 of the collar embraces the rim of the socket. The fit of the collar 19 upon the body of the socket is such that the collar is free to be rotated relatively to the fixed socket, the rear opening 22 of the collar, as defined by the circular edge of the radial flange 21, being sufficiently large to provide for such free projection therethrough of the spacer washers 18-18 and the mounting screws 17-17 as not to interfere with the rotation of the collar 19 relatively to the socket with which it is associated.

The annular body portion 20 of the rotatable collar is notched, as at 23, to reduce the width of said portion sufficiently to permit the free insertion and removal of the lamp prongs into and out of engagement with their associated spring contact elements in the socket when the collar is rotated into the positions shown in Figures 1, 2 and 4. It will be noted that the notch 23 in the annular wall 20 of the collar provides an entrance opening into the slots 16-16 of the socket which is only slightly greater than the overall distance across both slots 16-16, the opposite edges of the notch 23 being spaced approximately 90 degrees apart. Consequently, upon rotation of the collar 19 through an angle of 180 degrees from its position shown in Figures 2 and 4, the open ends of the socket slots 16-16 are closed by the annular wall of the collar and so prevent dropping of the end of the lamp out of its socket should the prongs 14-14 become free of their spring contact elements 15-15.

As most clearly appears in Figures 6 and 7, the annular wall of the collar 19 is provided along its frontal edge with an outwardly turned flange 24 which terminates in a semi-circular rim portion 25 extending forwardly of and in coaxial relation to the annular body portion 20 of the collar. This semi-circular rim portion 25 is located diametrically opposite the notch 23 and is of a radius which so corresponds to that of the end of the tubular lamp 13 that when the collar is rotated into its position shown in Figures 3 and 5, said rim portion 25 affords a positive arcuate support for the lamp end independent of the interengaged prongs and contact elements. Preferably, but not necessarily, the outer rim portion 25 of the rotatable collar 19 is provided at its opposite ends with radially extending terminal tabs 26-26 to facilitate rotation of the collar from its inoperative position shown in Figures 2 and 4 into its operative, lamp supporting position shown in Figures 3 and 5. It will be apparent that when in this latter position the collar 19 retains the tubular lamp in position against displacement from its socket even when the lighting unit is subjected to the most severe vibration.

The lamp supporting collar of the present invention is of simple construction and is readily

mounted upon the socket, with which it is associated by slipping it over the rear end thereof, the collar itself being then retained in position upon the socket when the latter is secured to its mounting bracket 11 as shown and hereinbefore described.

It will be understood, of course, that the present invention is susceptible of various changes and modifications which may be made from time to time without departing from the real spirit or general principles thereof, and it is accordingly intended to claim the invention broadly, as well as specifically, as indicated by the appended claims.

What is claimed as new and useful is:

1. A fitting for a tubular discharge lamp of the type having end terminal pins for engagement with the contact elements of a socket with which said lamp is associated, said fitting comprising a circumferentially continuous annular member rotatably carried by the socket and having a semi-circular rim of a radius sufficiently large to snugly embrace the end of the lamp immediately adjoining the socket, said rim extending axially beyond the lamp-adjoining or front face of the socket and being provided at its rear edge with an inwardly turned annular flange overlying the rear face of the socket.

2. A supporting fitting for a tubular discharge lamp adapted for operative association with a lamp socket of the type having a pair of laterally spaced open-ended slots for receiving the contact prongs of the lamp, said fitting being rotatably carried by the socket and including a circumferentially continuous rim having a portion thereof cut out to provide a notch through which the terminal prongs of the lamp may freely pass when the lamp is inserted into the socket, said rim being further provided at the side thereof diametrically opposed to said notch with an arcuate flange extending axially beyond the outer face of the socket and of a radius sufficient to snugly embrace the end of the lamp immediately adjoining said outer face of the socket, said notch extending circumferentially about the rim through an arc of sufficient extent to expose the lamp-prong-receiving slots of the socket when the fitting is rotated to position the said arcuate lamp-embracing flange above the longitudinal axis of the lamp.
